CLAUDE HAMILTON FITZ GERALD AND GEORGE HARCOURT HUTCHINS, OF KENTON,
ENGLAND.

CLEANING DEVICE FOR TOBACCO PIPES AND OTHER ARTICLES.

Application filed September 8, 1925, Serial No. 54,974, and in Great Britain August 22, 1925.

Our invention relates to devices for cleaning tobacco pipes, cigar and cigarette holders and other articles.

Our invention has for its object to provide an improved device of the type indicated above.

Referring now to the accompanying drawings, which are on a somewhat enlarged scale for the purposes of illustration,

Figure 1, shows an elevation of one form of cleaning device for a tobacco pipe, constructed according to our invention, while,

Figure 2, shows a plan view, partly in section, of the device shown in Figure 1, with the casing removed.

Figure 3, is a detail view showing the end of the tube and the internal rod illustrated in Figures 1 and 2, the internal rod being in the projected position, that is, in position to receive the material.

Fig. 3a is a view similar to Fig. 3 with the internal rod in retracted position, that is in position to grip the material.

Figure 4, shows an elevation, partly in section of a modified form of mechanism for actuating the internal rod, while,

Figure 5, is a cross-section through the line V—V on Figure 4.

Figure 6, shows a sectional elevation of a further modification, while,

Figure 7, shows a detail plan of the slot in the handle portion illustrated in Figure 6.

In carrying our invention into effect, according to one form and as applied by way of example to a device for cleaning tobacco pipes, we construct the device with a cylindrical handle portion, 1, Figures 1 and 2, to one end of which a straight tube, 2, is rigidly secured. The tube, 2, and the handle portion, 1, may be secured together by screwing or in any other suitable manner.

Within the tube, 2, a rod, 3, is disposed so as to be slidably mounted therein, the outer end of the rod being bifurcated and provided with inturned barbs, 4, on the jaws, 5, of the bifurcated end. The material of which the rod is formed is preferably such that the jaws, 5, are resilient and tend to spring apart from one another.

The inner end of the internal rod, 3, projects within the handle portion, 1, and is connected to the arm, 7, of a two-armed lever, which is pivotally mounted on a bearing, 8, on the handle portion, 1. The arm, 7, of the lever, which is connected to the internal rod,

3, projects within the handle portion, 1, while the other arm, 9, of the lever is disposed externally on the handle portion, 1.

The above arrangement is such that by actuating the external arm, 9, of the lever, 60 the internal rod, 3, may be moved lengthwise relatively to the tube, 2, for a certain distance in either direction as desired.

A tubular casing, 10, closed at one end, is adapted to enclose the tube, 2, the open end of the casing being threaded and engaging with a corresponding threaded part of the handle portion, 1, or the end of the casing, 10, may make a tight push-fit with the handle portion, 1. The casing, 10, thus acts as 70 a protector for the tube, 2.

The handle portion, 1, may preferably be formed in two hollow or recessed portions which are adapted to be screwed together, or to make a tight push-fit with one another 75 so as to form a receptacle, 11, for the knitting wool or other material which is used for cleaning the pipe.

In the operation of the device, the casing, 10, is removed and a length of knitting wool 80 abstracted from the receptacle, 11, in the handle portion, 1. The lever is then actuated by its external arm, 9, so that the bifurcated end of the internal rod, 3, projects a suitable distance beyond the end of the 85 tube, 2, and the jaws, 5, of the rod have separated from one another as shown in Figure 2.

The middle portion of the piece of wool, 12, is then inserted between the jaws, 5, and 90 the lever manipulated by its external arm, 9, in the opposite direction so that the projecting end of the internal rod, 3, is partially or wholly retracted within the tube, 2, as shown in Figure, 3. This movement of the 95 internal rod, 3, causes the jaws, 5, thereof to be forced together and grip the wool tightly therebetween.

The tube, 2, having the wool, 12, secured to the end thereof, is then inserted in the 100 stem of the pipe to be cleaned, and moved to and fro therein so as to thoroughly clean it, after which the tube, 2, is removed from the pipe stem and the external arm, 9, manipulated so as to open the jaws, 5, of the 105 internal rod, 3. The soiled wool may then be released by shaking it free from the end of the internal rod, 3, or in any other convenient manner.

Instead of using a lever for the manipula- 110

tion of the internal rod, 3, as above described, in some cases we may form the inner end of the internal rod, 3, of square section, Figures 4 and 5, the squared part, 13, thereof sliding in a correspondingly formed hole or recess, 14, in an oval-shaped handle portion, 1. A thread, 15, is formed on the part, 13, and engages with a milled nut, 16, mounted in the handle portion, 1, from which oppositely disposed portions, 17, Figure 5, of the nut project, so that by manipulating the projecting portions, 17, of the nut, 16, the internal rod, 3, may be actuated in a similar manner to that above described.

Again, the inner end of the internal rod, 3, Figures, 6 and 7, may be bent at right angles and have a knob, 18, formed on the bent end thereof, the bent end projecting through a slot, 19, in the handle portion, 1, so that the internal rod, 3, may be moved directly by actuating the knob, 18, longitudinally on the handle portion, 1. The internal rod, 3, may be strengthened at the bend by a suitably formed angular piece, 20, and a notch, 21, may be formed on the slot, 19, Figure 7, for retaining the knob, 19, and the internal rod, 3, in the retracted position.

In the forms of our invention shown in Figures 4 and 6, only the removable part of the handle portion, 1, is recessed to form the receptacle, 11, for the cleaning material.

Any other suitable means may be used for effecting the movement of the internal rod.

In some cases we may arrange to move the tube, 2, instead of the internal rod, 3, which in these circumstances will be rigidly secured to the handle portion, 1.

The devices which we have above described may preferably be provided with a clip, 22, for securing them to the pocket of the user.

The above devices may preferably be formed of metal throughout, or, if desired, certain parts, such as the handle portion and the casing, may be formed of vulcanite or other suitable non-metallic material, or the whole of the parts may be formed of vulcanite or other suitable non-metallic material, if desired.

Further, the tube, 2, and the internal rod, 3, may be of sufficient flexibility so as to be adapted for cleaning pipes with slightly curved stems as well as straight stems, in the case of pipes with greatly curved stems, however, the tube, 2, and the internal rod, 3, may be curved to suit the curvature of the stems, or the tube, 2, may be formed as a flexible metallic or non-metallic tube.

Although we have described our invention as applied by way of example to a device for cleaning tobacco pipes, its use is not limited to this application, as it may also be applied to devices for cleaning cigar and cigarette holders as well as to devices for cleaning other articles.

By means of our invention, an efficient form of cleaning device is provided which may, if desired, be carried in the pocket of the user and which is efficiently protected from liability to breakage and from soiling articles with which it may come into contact. Also the used wool or other material used in the cleaning operation may be released from the device without handling.

Modifications may be made in the detail and arrangement of the examples of our invention above described.

We claim:

1. A pipe cleaner having in combination, movable members together with means for effecting a relative movement of said members longitudinally for the application of cleaning material thereto and another relative movement for gripping the applied material.

2. A pipe cleaner having in combination relatively movable members together with means for reciprocating one of said members relatively to the other of said members so as to project the reciprocable member beyond the other of said members for the application of cleaning material thereto, and to retract said reciprocable member for gripping the applied cleaning material.

3. A pipe cleaner having in combination co-axial members movable relatively to one another together with means for reciprocating one of said members longitudinally relatively to the other of said members so as to project the reciprocable member beyond the other of said members for the application of cleaning material thereto and to retract said reciprocable member for gripping the applied cleaning material.

4. A pipe cleaner having in combination a tube, a rod co-axial with said tube together with means for reciprocating said rod relatively to said tube so as to partially project said rod for the application of cleaning material thereto and to retract said rod for gripping the applied cleaning material.

5. A pipe cleaner having in combination a tube, a rod co-axial with said tube and having engaging means for cleaning material on one of its ends, means for reciprocating said rod longitudinally relatively to said tube so as to cause the engaging means on said rod to project from said tube for the application of cleaning material to said engaging means and for retracting said rod to cause the applied cleaning material to be gripped by said engaging means.

6. A pipe cleaner having in combination a tube, a rod co-axial with said tube and having one of its ends bifurcated, together with means for reciprocating said rod longitudinally relatively to said tube so as to cause the bifurcated end of said rod to project from said tube for the application of cleaning material to said bifurcated end and

for retracting said rod to cause the applied cleaning material to be gripped by said bifurcated end.

7. A pipe cleaner comprising a handle portion formed in part to provide a receptacle, a tube of restricted diameter projecting from one end of the handle portion, a rod slidably mounted in the tube and having the end remote from the handle portion formed to permit the interconnection therewith of a cleaning substance, and means in

the handle portion connected with the rod to reciprocate the rod longitudinally of the tube, whereby to project the rod beyond the end of the tube to permit the application of the cleaning substance and to then withdraw the rod and cleaning substance partly within the tube. 15

In testimony whereof we have signed our names to this specification.

CLAUDE HAMILTON FITZ GERALD.
GEORGE HARCOURT HUTCHINS.
